UNITED STATES PATENT OFFICE.

GEORGE M. J. MACKAY, OF SCHENECTADY, NEW YORK, ASSIGNOR TO GENERAL, ELECTRIC COMPANY, A CORPORATION OF NEW YORK.

INCANDESCENT LAMP.

1,239,413.

Specification of Letters Patent. Patented Sept. 4, 1917.

Application filed December 20, 1913, Serial No. 807,817. Renewed March 25, 1913. Serial No. 26,793.

To all whom it may concern:

Be it known that I, GEORGE M. J. MACKAY, a subject of the King of Great Britain, residing at Schenectady, county of Schenectady, State of New York, have invented certain new and useful Improvements in Incandescent Lamps, of which the following is a specification.

The present invention relates to the construction of the incandescent body, or filament of an incandescent lamp, and particularly to the type of lamp in which a refractory filament is operated at intensive incandescence, particularly in a gas.

In accordance with my invention the filament is shaped so as to secure a desired distribution of temperature which in general should be substantially uniform and to secure mechanical stability of the filament when pliable at a high temperature. With these ends in view, sections of the filament subject to overheating and deformation by natural forces such as gravity or the magnetic field of the operating current are given greater heat-dissipating capacity than the remainder of the filament. The novel features of my invention are pointed out with particularity in the appended claims.

My invention is illustrated in the accompanying drawings in which Figure 1 shows in outline a lamp provided with a filament disposed in accordance with my invention and Figs. 2 and 3 illustrate the filaments on an enlarged scale.

A refractory conductor, for example, metallic tungsten, if of sufficient size, or proper configuration, may be operated at a very high temperature in a gas, such as nitrogen, argon, or mercury vapor, so that the increase of light more than offsets the increase of heat loss and a net gain of efficiency is secured over operation in an evacuated space. The gaseous atmosphere reduces the vaporization of the filament and also causes deposition of vaporized material at regions remote from the filament, where it will not obscure the light.

As explained more fully in Patent No. 1,180,159, issued to Irving Langmuir, the heat losses from the filament in a lamp of this character may be reduced by concentrating the filaments in a given space, as by coiling them preferably in helical form.

My experiments have shown that when

the filament is pliable while at incandescence the shape of the coil or helix may vary irregularly, some of the turns being drawn together by magnetic attraction and other turns may partially open up by the weight of the remaining turns suspended thereto, thereby deleteriously varying the temperature of the filament and the characteristics of the lamp.

Fig. 1 shows a gas-filled lamp which is commonly of elongated shape. The filament 1 preferably consists of malleable tungsten. It is usually located near the lower part of the glass bulb 2. The filament is supported at its ends by being welded, or otherwise connected to conductors 3, 4, 70 sealed in a glass stem 5.

It will be noted that the lowermost turns of the filament are freely suspended as they support but their own weight. When pliable at high incandescence they are apt to be drawn together by the magnetic force of the heating current, thereby overheating this part of the filament and eventually causing short-circuiting of a part of the filament by actual contact of the turns with each other. 70 The upper turns of the helix receive heat by gas convection currents from the lower part of the helix in addition to the heat electrically developed, and hence this part of the filament will tend to operate at an excessive 85 temperature.

In accordance with my invention the adjacent filament turns constituting the section or sections which are to be given an increased heat dissipating capacity, are spaced 80 apart a greater distance than the turns constituting the remainder of the filament.

In Figs. 2 and 3 the distances between the turns of the helix have been shown somewhat exaggerated. Ordinarily the closely spaced 95 turns are apart a space less than the diameter of the filament. As shown in Fig. 2 the turns 6 at the bight of the filament loop and the upper turns 7 are spread preferably by inserting spacers when the helix is prepared, 100 these spacers being subsequently removed.

It is ordinarily unnecessary to spread the turns 8 immediately adjoining the supports, as heat is conducted away at this region by the supports. In some instances, special provision may be made to prevent the cooling action of the leads by reducing the cross-section of the filament in contact with the leads. 105

In that event fewer turns may be spaced close together near the point of contact of the filament with the support.

By thus spacing the turns more widely at 5 the regions subject to overheating the energy dissipation at these regions is increased. The lowermost turns not only operate somewhat cooler and are rendered somewhat stiffer but the tendency to close up is less as magnetic 10 attraction varies with the square of the distance and consequently its effect is materially reduced, and therefore, both overheating and short-circuiting is avoided.

In some cases the spreading of the upper 15 turns of the helix may be omitted as shown in Fig. 3. In this case the upper turns will sag somewhat after the lamp is running and the candle power of the lamp vary a corresponding extent. In some cases the spreading 20 of the lower turns may be displaced slightly upward, the very lowest turns being quite close together and the turns next adjoining being opened up somewhat. In this the lowest turns are cooled by heat conduction 25 through the wire to the adjoining region where greater heat dissipation occurs.

What I claim as new and desire to secure by Letters Patent of the United States, is:—

1. An incandescent lamp comprising an 30 envelop and a coiled filament therein suspended at the terminals only and having turns subject to overheating spaced more widely apart than the remaining turns.

2. An incandescent lamp containing a 35 freely suspended helical filament having a plurality of adjacent turns subject to deformation by natural forces during operation and spaced apart more widely than other adjacent turns, whereby substantially uniform incandescence during the life of the 40 lamp is secured.

3. An incandescent lamp comprising an

envelop and a helically coiled loop-shaped filament supported therein, the turns of which tending to overheat during operation are 45 spaced a greater distance apart than adjacent turns, to secure incandescence of the filament helix at a substantially uniform temperature during the life of the lamp.

4. An incandescent lamp comprising the 50 combination of an envelop, a filling of gas therein, a coiled tungsten filament therein having turns most subject to distorting forces spaced apart a greater distance than other turns.

5. An incandescent lamp comprising the 55 combination of an envelop, a filling of inert gas therein and a helical refractory metal filament which is pliable at operating temperature of the lamp said filament having a 60 few of the lowermost turns and a plurality of the upper turns spaced apart a greater distance than other turns.

6. An incandescent lamp comprising the 65 combination of an envelop a looped helically coiled filament within said envelop and supports for the terminals only of said filament, the coils at the bight of said filament loop being spaced apart more widely than the adjacent coils.

7. An incandescent lamp comprising the 70 combination of an envelop, a filling of inert gas therein, and a helical filament therein supported at its terminals, the lowermost coils of said filament being at a greater distance from each other than the remaining coils.

In witness whereof, I have hereunto set my hand this 18th day of December, 1913.

GEORGE M. J. MACKAY.
